METHOD OF SPLICING HEAVY DUTY CABLE

Ernest M. Blue, Houston, Tex.

Application September 20, 1955, Serial No. 535,488

4 Claims. (Cl. 154—2.22)

This invention relates to a method of splicing cable.

An object of the present invention is to provide a method of splicing cable which enables the repair by splicing of a damaged or broken cable.

Another object of the present invention is to provide a method of splicing cable which enables the repair of a heavy duty cable by splicing at its location of use.

A further object of the present invention is to provide a method of splicing cable which is simple, positive in execution, and commercially feasible.

Other objects and advantages of the invention will become apparent from the following description taken with the accompanying drawings in which:

Figures 1, 2, 2A, 2B, 3, 3A, 3B, 4, 5, 6, 7, 7A, 7B, 7C, 8, 9, 9A, 9B, and 10 graphically illustrate the steps of the method according to the present invention.

The method of the present invention is especially applicable to the splicing of cable for use in oil drilling operations and of the type including a core of plurality of conductive wires twisted about each other, a rubber casing housing said core, a flexible fabric sheathing encasing said rubber casing, an inner lay of wires wrapped about said sheathing in one direction, and an outer lay of wires wrapped about said inner lay in the opposite direction. More particularly, the method of the present invention is for the splicing of said cable in which the wires comprising each of the inner and outer lays is eighteen in number, and such method will be herein-after described in connection with a cable having the aforesaid number of wires in the inner and outer lays.

In carrying out the method of the present invention, a first portion having a free end of the aforesaid type of cable and generally indicated by the numeral 10, Figure 1, is provided, and a second portion having a free end of the aforesaid type of cable, and generally indicated by the numeral 20, is also provided. Preferably, the portions 10 and 20 should be of the same length, and in this instance, the length is 22 feet.

The wires of the outer lay 11 of the first portion 10, Figure 2, are folded back from the free end thereof in multiples 11a, in this instance, multiples of 3 each, and for a predetermined length, in this instance, adjacent the opposite end of the measured length of 20 feet. Next, the wires of the inner lay 12 of the first portion 10, are folded back from the free end thereof in multiples 12a in this instance multiples of 3 each and for a length substantially the same as that of the wires of the outer lay 11, in this instance, adjacent the opposite end of the measured length of 20 feet and the free end portions of the multiples 12a coiled as shown in Figure 2A. With the folding back of the wires in multiples 12a of the inner lay 12 of the portion 10 this uncovers the adjacent portion of the core of the cable and housed by the rubber covering and the fabric sheathing encasing such covering and generally indicated by the numeral 13. Next, a length is measured on the uncovered core from the folded back multiples 12a of the inner lay 12 toward

the free end of the portion 10, in this instance about 9 inches, and a marking of the terminating point of the measured length marked on the exposed core portion. Then, a segment 14 of the rubber covering housed by the fabric sheathing and indicated by the numeral 13 is removed, such segment extending from the free end of the portion 10 to a point spaced from the free end of the portion 10 or the terminating point of the measured length marked on the exposed core portion, as depicted in Figure 2A.

The free end portion of the rubber covering housed by the fabric sheathing 13 is pushed inwardly, Figure 2B, to expose the conductive wires of the core 16 and such free end portion fastened to the underneath part of the core. The exposed conductive wires of the core 16 are then separated into at least two strands or strands 15.

The wires of the outer lay 21 of the second portion 20, Figure 3, are folded back from the free end thereof in multiples 21a, in this instance multiples of 9 each, and for a predetermined length, in this instance 3 feet from the free end of the portion 20. Next, the wires of the inner lay 22 of the second portion 20, Figure 3A, are folded back from the free end thereof in multiples 22a, in this instance, multiples of 3 each, and for a length less than that of the outer lay 21 of the portion 20, in this instance 1 foot from the free end of the portion 20. With the folding back of the wires in multiples 22a of the inner lay 22 of the portion 20 this uncovers adjacent portion of the core of the cable and housed by the rubber covering and the fabric sheathing encasing such covering and generally indicated by the numeral 23. Next, the free end portion of the rubber covering housed by the fabric sheathing is pushed inwardly, Figure 3B, to expose the conductive wires of the core 26 and such free end portion fastened to the underneath part of the core. The exposed conductive wires of the core 26 are then separated into at least two strands or strands 25.

The strands 25 of the separated core part of the second portion 20 and the strands 15 of the separated core part of the first portion 10 are twisted about each other to form an interconnected section generally indicated by the numeral 30, Figure 4, connecting the cores 26 and 16 of the portions 20 and 10 together. The interconnected section is then integrally connected to the rubber casings.

This is done by wrapping a binding tape 31 about the interconnected section 30. Upon completion of the wrapping of the binding tape about the section 30 the two free end portions of the rubber casing-sheathings 23 and 13 are released and shifted so that the free ends are adjacent to and spaced from each other, Figure 5. The portion of the fabric sheathings adjacent the free ends of the rubber casings are removed, whereupon the free ends of the rubber casings are vulcanized to form a one-piece rubber casing about the connected section 30. An insulating tape 32, Figure 6, is then wrapped about the rubber casing corresponding to the interconnected section 30.

Upon completion of the wrapping of the insulating tape 32 about the rubber casing corresponding to the interconnected section 30, the folded back wire multiples 12a of the inner lay 12 of the first portion 10, Figure 7, are successively wrapped about the insulating tape 32 on the interconnected section 30 up to the folded back wire multiples 22a of the inner lay 22 of the second portion 20 and lock the respective wrappings together about the section 30. At this point the two folded back wire multiples 21a of the outer lay 21 are folded back to practically the remaining eighteen feet or to the point adjacent the terminating point or other end of the 22 foot first

portion 20 or as indicated in dotted lines in Figure 7, whereupon one of the multiples 22a of the inner lay 22 of the second portion 20 is unlocked from the adjacent one of the multiples 12a of the inner lay 12 of the first portion 10 and is unwrapped until it is adjacent to and spaced a predetermined length from the folded back multiples 21a of the outer lay 21 of the second portion 20, or in this instance a length of 3 feet and indicated by the letter A in Figure 7A. Next, the adjacent one of the multiples 12a of the inner lay 12 of the first portion 10 is wrapped in the space vacated by the unwrapped one multiple 22a of the second portion 20 until the free end portion engages the unwrapped one multiple 22a of the inner lay 22 of the second portion 20 and lock the wrapped multiple to the unwrapped multiple. Upon conclusion of the locking of the wrapped multiple with the unwrapped multiple, a second of the five remaining multiples 22a of the inner lay 22 of the second portion 20 is unlocked from the adjacent one of the multiples 12a of the inner lay 12 of the first portion 10 and is unwrapped until it is adjacent to and spaced a predetermined length from the locked one wrapped multiple to the unwrapped multiple indicated by the letter A or in this instance, the same length or 3 feet, and indicated by the letter B in Figure 7A, whereupon the adjacent second one of the multiples 12a of the inner lay 12 of the first portion 10 is wrapped in the space vacated by the unwrapped second one of the multiples 22a of the second portion 20 until the free end portion engages the unwrapped second one of the multiples 22a of the inner lay 22 of the second portion 20, and lock the wrapped multiple to the unwrapped multiple. This unwrapping of each of the remaining four multiples 22a of the inner lay 22 of the second portion 20 followed by the wrapping of the adjacent one of the multiples 12a of the inner lay 12 of the first portion 10 vacated by the unwrapped multiple with the free end portion of the wrapped multiple engaged and locked to the unwrapped multiple is performed in turn, but with the four remaining complemental locked wrapped and unwrapped multiples 12a and 22a spaced the same length from each other or in this instance 3 feet. In Figure 7A, the letter B indicates the terminating point of the third complemental locked wrapped and unwrapped multiples 12a and 22a spaced a length of 3 feet from the terminating point A of the second complemental locked wrapped and unwrapped multiples.

Upon conclusion of the wrapping and unwrapping of the respective pairs of multiples 12a and 22a one of the wires is separated from the engaged unwrapped said one multiple 22a of the inner lay 22 of the second portion 20, letter A of Figure 7A, and said one wire is unwrapped until it is adjacent to and spaced a multiple of the length of the spacing of the engaged said one wrapped and unwrapped multiples 12a and 22a from the folded back multiples 21a of the outer lay 21 of the second portion 20, such multiple in this instance being one foot as shown in Figure 3B, whereupon one of the wires is separated from the engaged wrapped said one multiple 12a of the inner lay 12 of the first portion 10 and wrapped in the space vacated by the unwrapped one wire of said one multiple 22a of the portion 20 until the free end portion engages the unwrapped one wire of the multiple 22a of the portion 20 and lock the wrapped wire to the unwrapped wire. Following this, another one of the wires is separated from the engaged unwrapped said one multiple 22a of the inner lay 22 of the second portion 20, letter A of Figure 7A, and said another wire is unwrapped until it is adjacent to and spaced a multiple of the length of the spacing of the engaged said one wrapped and unwrapped multiples 12a and 22a from the folded back multiples 21a of the outer lay 21 of the second portion 20 corresponding to the same length multiple as that of said engaged one wrapped and unwrapped wires of the pair of multiples 12a and 22a of the portions 10 and 20, the latter multiple being in this instance one foot, whereupon another one of the

wires is separated from the engaged wrapped said one multiple 12a of the inner lay 12 of the first portion 10 and wrapped in the space vacated by the unwrapped another wire of said one multiple 22a of the portion 20 until the free end portion engages the unwrapped another wire of the multiple 22a of the portion 20 and lock the wrapped another wire to the unwrapped another wire. This leaves the further and remaining one of the wires of the one multiple 22a of the inner lay 22 of the second portion 20, at the position indicated by the letter A in Figure 7B engaged by the further and remaining one of the wires of the one multiple 12a of the inner lay 12 of the first portion 10. The above described procedure as to the separation and unwrapping of the wires of one of the multiples 22a of the second portion 20 and separation and wrapping of the wires of one of the multiples 12a of the first portion 10 is repeated in turn with each of the remaining five multiples 22a of the second portion 20 and the complemental multiples 12a of the first portion 10 until they are all in complemental groups, Figure 7B showing graphically that most of the pairs of wires are in assembled condition with several in process of assembled condition. At this point the excess wires of each pair is removed, and each pair in turn subjected to a welding operation which welds the wrapped wire to the adjacent wires, as graphically depicted in Figure 8. Figure 7C illustrates the assembled inner lay of the spliced cable, the number 28 indicating the respective welds in the inner lay.

Upon completion of the formation of the assembled inner lay of the spliced cable the two folded back multiples 21a of 9 wires each of the outer lay 21 of the second portion 10 are wrapped about such assembled inner lay until the free end portions are adjacent the folded back multiples 11a of the outer lay 11 of the first portion 10, the free end portions of each of the two folded back multiples 21a being then subdivided into three multiples with each multiple having three wires. This results in the free end portions of the two multiples 21a being subdivided into six multiples, with each multiple having three wires, as illustrated in Figure 9. Each free end portion of the six multiples 21a is engaged by the free end portion of one of the multiples 11a and lock the two multiples together. Next, one of the multiples 21a of the outer lay 21 of the second portion 20 is unlocked from the adjacent one of the multiples 11a of the outer lay 11 of the first portion 10 and is unwrapped until it is adjacent to and spaced a predetermined length from the terminating end indicated by the numeral 29, Figure 9, of the second portion 20 or in this instance a length of 3 feet from the end 29, whereupon the adjacent and unlocked one of the multiples 11a is wrapped in the space vacated by the unwrapped one multiple 21a until the free end portion engages the unwrapped one multiple 21a and lock the wrapped multiple to the unwrapped multiple. Upon conclusion of the locking of the wrapped multiple with the unwrapped multiple, a second of the five remaining multiples 21a is unlocked from the adjacent one of the multiples 11a and is unwrapped until it is adjacent to and spaced a predetermined length from the locked one wrapped multiple or in this instance the same length as the first one locked wrapped and unwrapped multiple from the end 29 or 3 feet, whereupon the adjacent second one of the multiples 11a of the first portion 10 is wrapped in the space vacated by the unwrapped second one of the multiples 21a of the second portion 20 until the free end portion engages the unwrapped second one of the multiples 21a. This unwrapping of each of the remaining four multiples 21a followed by the wrapping of the adjacent one of the multiples 11a vacated by the unwrapped multiple with the free end portion of the wrapped multiple engaged and locked to the unwrapped multiple is performed in turn, but with the four remaining complemental locked wrapped and unwrapped mul-

tips 11a and 21a spaced the same length from each other or in this instance 3 feet. Figure 9A shows a portion of the spliced cable after the aforesaid wrapping and unwrapping of the respective pairs of multiples 11a and 21a have been concluded, the fifth and sixth pairs with their terminating points E and F being only shown.

Upon conclusion of the wrapping and unwrapping of the respective pairs of multiples 11a and 21a one of the wires is separated from the engaged unwrapped said one multiple 21a and said one wire is unwrapped until it is adjacent to and spaced a multiple of the length of the spacing of the engaged said one wrapped and unwrapped multiples 11a and 21a from the terminating point 29 of the second portion 20, such multiple being 1 foot, whereupon one of the wires is separated from the engaged wrapped said one multiple 11a and wrapped in the space vacated by the unwrapped one wire of said one multiple 21a until the free end portion engages the unwrapped one wire of the multiple 21a and lock the wrapped wire to the unwrapped wire. Following this, another one of the wires is separated from the engaged unwrapped said one multiple 21a and said another wire is unwrapped until it is adjacent to and spaced a multiple of the length of the spacing of the engaged said one wrapped and unwrapped multiples 11a and 21a from the terminating point 29 of the second portion 20, corresponding to the same length multiple as that of said engaged one wrapped and unwrapped wires of the pair of multiples 11a and 21a, the latter multiple being in this instance one foot, whereupon another one of the wires is separated from the engaged wrapped said one multiple 11a and wrapped in the space vacated by the unwrapped another wire of said one multiple 21a until the free end portion engages the unwrapped another wire of the multiple 21a and lock the wrapped another wire to the unwrapped another wire. The further and remaining one of the wires of the one multiple 21a is at the position or length from the terminating point 29 of the second portion 20 or 3 feet and is engaged by the further and remaining one of the wires of the one multiple 11a. The above described procedure as to the separation and unwrapping of the wires of one of the multiples 21a and separation and wrapping of the wires of one of the multiples 11a is repeated in turn with each of the remaining five multiples 21a and complementary multiples 11a until they are all in complementary groups. Figure 9B illustrates a portion of the spliced cable after the aforesaid wrapping and unwrapping of the wires of the respective pairs of multiples 11a and 21a have been concluded, the fourteenth to the eighteenth pairs being only shown. At this point the excess wires of each pair is removed, and each pair in turn subjected to a welding operation which welds the wrapped wire to the adjacent wires, as graphically depicted in Figure 8, and previously described. Figure 10 shows a portion of the completed spliced cable obtained by the foregoing described process, the number 40 indicating the respective welds in the outer lay.

The spliced cable resulting from the practice of the above described method is sturdy and is capable of withstanding the shocks and conditions of hard usage when employed in oil drilling operations.

Having thus described the invention what is new and desired to be secured by Letters Patent is:

1. The method of splicing cable of the type including a core of plurality of conductive wires twisted about each other, a rubber casing housing said core, an inner lay of wires wrapped about said casing in one direction, and an outer lay of the same number of wires as said inner lay wrapped about said inner lay in the opposite direction comprising providing a first portion having a free end of said cable, folding back from the free end of said first portion in multiples and for a predetermined length the wires of the outer lay thereof, folding back from the free end of said first portion in multiples and for a length substantially the same as that of said outer lay the

wires of the inner lay thereof, removing a segment of the rubber casing extending from the free end of said portion to a point spaced from said free end, pushing inwardly the free end portion of the rubber casing of said portion to expose the conductive wires of the core and fastening it to the underneath portion of the core, separating the wires of said exposed core part into at least two strands, providing a second portion having a free end of said cable, folding back from the free end of said second portion in multiples and for a predetermined length the wires of said second portion outer lay, folding back from the free end of said second portion in multiples and for a length less than that of the outer lay of said first portion the wires of the inner lay of said second portion, pushing inwardly the free end portion of the rubber casing of said second portion to expose the conductive wires of the core and fastening it to the underneath portion of the core, separating the wires of said exposed part of said second portion into at least two strands, twisting the strands of the separated core part of said first portion about the strands of the separated core part of said second portion to form an interconnected section connecting the cores of said first and second portions together, integrally connecting the rubber casings of said first and second portions to said interconnected sections to form a one-piece rubber casing, wrapping the folded back wire multiples of the inner lay of said first portion successively about the one-piece rubber casing on the interconnected section up to the folded back wire multiples of the inner lay of said second portion and lock the respective wrappings together about said section, unwrapping one of the folded back wire multiples of the inner lay of said second portion until it is adjacent to the folded back wire multiples of the outer lay of said second portion, wrapping one of the folded back multiples of the inner lay of said first portion in the space vacated by the unwrapped one multiple of said second portion with the free end portion engaging said unwrapped one multiple of the inner lay of said second portion and lock the wrapped multiple to the unwrapped multiple, unwrapping another of the folded back wire multiples of the inner lay of said second portion until it is spaced a predetermined length from the locked free end portion of said one wrapped multiple of the inner lay of said first portion, wrapping another of the folded back wire multiples of the inner lay of said first portion in the space vacated by the unwrapped another multiple of said second portion with the free end portion engaging said unwrapped another multiple of the inner lay of said second portion and lock the wrapped multiple to the unwrapped multiple, separating one of the wires from the engaged unwrapped one multiple of the inner lay of said second portion and unwrapping said one wire until it is adjacent to and spaced a multiple part of the length of the spacing of the engaged said one wrapped and unwrapped multiple of said first and second portions from the folded back multiples of the outer lay of said second portion, separating one of the wires from the engaged wrapped one multiple of the inner lay of said first portion and wrapping said one wire in the space vacated by the unwrapped one wire of the one multiple of the inner lay of said second portion with the free end portion engaging said unwrapped one wire of the one multiple of the inner lay of said second portion and lock the wrapped one wire to the unwrapped one wire, separating another of the wires from the engaged unwrapped another multiple of the inner lay of said second portion and unwrapping said another wire until it is adjacent to and spaced a length from said engaged one wrapped and unwrapped multiples of said first and second portions corresponding to the same length multiple as that of said engaged one wrapped and unwrapped wires of the multiples of said first and second portions, separating another of the wires from the engaged unwrapped another multiple of the inner lay of said first portion and wrapping said another wire in the space vacated by the unwrapped another wire of the

another multiple of the inner lay of said first portion with the free end portion engaging said unwrapped another wire of the another multiple of the inner lay of said second portion and lock the wrapped another wire to the unwrapped another wire, and welding each of said one and another wrapped wires to the adjacent wires to form a unitary inner lay.

2. The method of splicing cable of the type including a core of plurality of conductive wires twisted about each other, a rubber casing housing said core, an inner lay of wires wrapped about said casing in one direction, and an outer lay of the same number of wires as said inner lay wrapped about said inner lay in the opposite direction comprising providing a first portion having a free end of said cable, folding back from the free end of said first portion in multiples and for a predetermined length the wires of the outer lay thereof, folding back from the free end of said first portion in multiples and for a length substantially the same as that of said outer lay the wires of the inner lay thereof, removing a segment of the rubber casing extending from the free end of said portion to a point spaced from said free end, pushing inwardly the free end portion of the rubber casing of said portion to expose the conductive wires of the core and fastening it to the underneath portion of the core, separating the wires of said exposed core part into at least two strands, providing a second portion having a free end of said cable, folding back from the free end of said second portion in multiples and for a predetermined length the wires of said second portion outer lay, folding back from the free end of said second portion in multiples and for a length less than that of the outer lay of said first portion the wires of the inner lay of said second portion, pushing inwardly the free end portion of the rubber casing of said second portion to expose the conductive wires of the core and fastening it to the underneath portion of the core, separating the wires of said exposed part of said second portion into at least two strands, twisting the strands of the separated core part of said first portion about the strands of the separated core part of said second portion to form an interconnected section connecting the cores of said first and second portions together, integrally connecting the rubber casings of said first and second portions to said interconnected section to form a one-piece casing, wrapping the folded back wire multiples of the inner lay of said first portion successively about the one-piece rubber casing on the interconnected section up to the folded back wire multiples of the inner lay of said second portion and lock the respective wrappings together about said section, unwrapping one of the folded back wire multiples of the inner lay of said second portion until it is adjacent to the folded back wire multiples of the outer lay of said second portion, wrapping one of the folded back multiples of the inner lay of said first portion in the space vacated by the unwrapped one multiple of said second portion with the free end portion engaging said unwrapped one multiple of the inner lay of said second portion and lock the wrapped multiple to the unwrapped multiple, unwrapping another of the folded back wire multiples of the inner lay of said second portion until it is spaced a predetermined length from the locked free end portion of said one wrapped multiple of the inner lay of said first portion, wrapping another of the folded back wire multiples of the inner lay of said first portion in the space vacated by the unwrapped another multiple of said second portion with the free end portion engaging said unwrapped another multiple of the inner lay of said second portion and lock the wrapped multiple to the unwrapped multiple, separating one of the wires from the engaged unwrapped one multiple of the inner lay of said second portion and unwrapping said one wire until it is adjacent to and spaced a multiple part of the length of the spacing of the engaged said one wrapped and unwrapped multiples of said first and second portions from

5 the folded back multiples of the outer lay of said second portion, separating one of the wires from the engaged wrapped one multiple of the inner lay of the said first portion and wrapping said one wire in the space vacated by the unwrapped one wire of the one multiple of the inner lay of said second portion with the free end portion engaging said unwrapped one wire of the one multiple of the inner lay of said second portion and lock the wrapped one wire to the unwrapped one wire, separating another of the wires from the engaged unwrapped another multiple of the inner lay of said second portion and unwrapping said another wire until it is adjacent to and spaced a length from said engaged one wrapped and unwrapped multiples of said first and second portions corresponding to the same length multiple as that of said engaged one wrapped and unwrapped wires of the multiples of said first and second portion, separating another of the wires from the engaged unwrapped another multiple of the inner lay of said first portion and wrapping said another wire in the space vacated by the unwrapped another wire of the another multiple of the inner lay of said first portion with the free end portion engaging said unwrapped another wire of the another multiple of the inner lay of said second portion and lock the wrapped another wire to the unwrapped another wire, repeating in sequence the above recited steps of separating and unwrapping and separating and wrapping of the remaining multiples of the inner lay of said second portion and of the remaining multiples of the inner lay of said first portion but with each of the resulting complementary locked wrapped and unwrapped multiples of said first and second portions spaced the same length from each other as that of said one and another complementary multiples, and welding each of said one, another, and each of the remaining wrapped wires to the adjacent wires to form a unitary inner lay.

3. The method of splicing cable of the type including a core of plurality of conductive wires twisted about each other, a rubber casing housing said core, an inner lay of wires wrapped about said casing in one direction, and an outer lay of the same number of wires as said inner lay wrapped about said inner lay in the opposite direction comprising providing a first portion having a free end of said cable folding back from the free end of said first portion in multiples and for a predetermined length the wires of the outer lay thereof, folding back from the free end of said first portion in multiples and for a length substantially the same as that of said outer lay the wires of the inner lay thereof, removing a segment of the rubber casing extending from the free end of said portion to a point spaced from said free end, pushing inwardly the free end portion of the rubber casing of said portion to expose the conductive wires of the core and fastening it to the underneath portion of the core, separating the wires of said exposed core part into at least two strands, providing a second portion having a free end of said cable, folding back from the free end of said second portion in multiples and for a predetermined length the wires of said second portion outer lay, folding back from the free end of said second portion in multiples and for a length less than that of the outer lay of said first portion the wires of the inner lay of said second portion, pushing inwardly the free end portion of the rubber casing of said second portion to expose the conductive wires of the core and fastening it to the underneath portion of the core, separating the wires of said exposed part of said second portion into at least two strands, twisting the strands of the separated core part of said first portion about the strands of the separated core part of said second portion to form an interconnected section connecting the cores of said first and second portions together, wrapping said interconnected section with a binding tape, releasing and shifting said two free portions of the rubber casing so that the free ends are adjacent to and spaced from each other,

vulcanizing together the free ends of the two rubber casing portions to form a one-piece rubber casing about said connected section, wrapping insulating tape about the rubber casing corresponding to said interconnected section, wrapping the folded back wire multiples of the inner lay of said first portion successively about the insulating tape on the interconnected section up to the folded back wire multiples of the inner lay of said second portion and lock the respective wrappings together about said section, unwrapping one of the folded back wire multiples of the inner lay of said second portion until it is adjacent to the folded back wire multiples of the outer lay of said second portion, wrapping one of the folded back multiples of the inner lay of said first portion in the space vacated by the unwrapped one multiple of said second portion with the free end portion engaging said unwrapped one multiple of the inner lay of said second portion and lock the wrapped multiple to the unwrapped multiple, unwrapping another of the folded back wire multiples of the inner lay of said second portion until it is spaced a predetermined length from the locked free end portion of said one wrapped multiple of the inner lay of said first portion, wrapping another of the folded back wire multiples of the inner lay of said first portion in the space vacated by the unwrapped another multiple of said second portion with the free end portion engaging said unwrapped another multiple of the inner lay of said second portion and lock the wrapped multiple to the unwrapped multiple, separating one of the wires from the engaged unwrapped one multiple of the inner lay of said second portion and unwrapping said one wire until it is adjacent to and spaced a multiple part of the length of the spacing of the engaged said one wrapped and unwrapped multiples of said first and second portions from the folded back multiples of the outer lay of said second portion, separating one of the wires from the engaged wrapped one multiple of the inner lay of said first portion and wrapping said one wire in the space vacated by the unwrapped one wire of the one multiple of the inner lay of said second portion with the free end portion engaging said unwrapped one wire of the one multiple of the inner lay of said second portion and lock the wrapped one wire to the unwrapped one wire, separating another of the wires from the engaged unwrapped another multiple of the inner lay of said second portion and unwrapping said another wire until it is adjacent to and spaced a length from said engaged one wrapped and unwrapped multiples of said first and second portions corresponding to the same length multiple as that of said engaged one wrapped and unwrapped wires of the multiples of said first and second portions, separating another of the wires from the engaged unwrapped another multiple of the inner lay of said first portion and wrapping said another wire in the space vacated by the unwrapped another wire of the another multiple of the inner lay of said second portion and lock the wrapped another wire to the unwrapped another wire and welding each of said one and another wrapped wires to the adjacent wires to form a unitary inner lay.

4. The method of splicing cable of the type including a core of plurality of conductive wires twisted about each other, a rubber casing housing said core, an inner lay of wires wrapped about said casing in one direction, and an outer lay of the same number of wires as said inner lay wrapped about said inner lay in the opposite direction comprising providing a first portion having a free end of said cable, folding back from the free end of said first portion in multiples and for a predetermined length the wires of the outer lay thereof, folding back from the free end of said first portion in multiples and for a length substantially the same as that of said outer lay the wires of the inner lay thereof, removing a segment of the rubber

casing extending from the free end of said portion to a point spaced from said free end, pushing inwardly the free end portion of the rubber casing of said portion to expose the conductive wires of the core and fastening it to the underneath portion of the core, separating the wires of said exposed core part into at least two strands, providing a second portion having a free end of said cable, folding back from the free end of said second portion in multiples and for a predetermined length the wires of said second portion outer lay, folding back from the free end of said second portion in multiples and for a length less than that of the outer lay of said first portion the wires of the inner lay of said second portion, pushing inwardly the free end portion of the rubber casing of said second portion to expose the conductive wires of the core and fastening it to the underneath portion of the core, separating the wires of said exposed part of said second portion into at least two strands, twisting the strands of the separated core part of said first portion about the strands of the separated core part of said second portion to form an interconnected section connecting the cores of said first and second portions together, integrally connecting the rubber casings of said first and second portions to said interconnected sections to form a one-piece casing, wrapping the folded back wire multiples of the inner lay of said first portion successively about the one-piece rubber casing on the interconnected section up to the folded back wire multiples of the inner lay of said second portion and lock the respective wrappings together about said section, unwrapping one of the folded back wire multiples of the inner lay of said second portion until it is adjacent to the folded back wire multiples of the outer lay of said second portion, wrapping one of the folded back multiples of the inner lay of said first portion in the space vacated by the unwrapped one multiple of said second portion with the free end portions engaging said unwrapped one multiple of the inner lay of said second portion and lock the wrapped multiple to the unwrapped multiple, unwrapping another of the folded back wire multiples of the inner lay of said second portion until it is spaced a predetermined length from the locked free end portion of said one wrapped multiple of the inner lay of said first portion, wrapping another of the folded back wire multiples of the inner lay of said first portion in the space vacated by the unwrapped another multiple of said second portion with the free end portion engaging said unwrapped another multiple of the inner lay of said second portion and lock the wrapped multiple to the unwrapped multiple, separating one of the wires from the engaged unwrapped one multiple of the inner lay of said second portion and unwrapping said one wire until it is adjacent to and spaced a multiple part of the length of the spacing of the engaged said one wrapped and unwrapped multiples of said first and second portions from the folded back multiples of the outer lay of said second portion, separating one of the wires from the engaged wrapped one multiple of the inner lay of said first portion and wrapping said one wire in the space vacated by the unwrapped one wire of the one multiple of the inner lay of said second portion with the free end portion engaging said unwrapped one wire of the one multiple of the inner lay of said second portion and lock the wrapped one wire to the unwrapped one wire, separating another of the wires from the engaged unwrapped another multiple of the inner lay of said second portion and unwrapping said another wire until it is adjacent to and spaced a length from said engaged one wrapped and unwrapped multiples of said first and second portions corresponding to the same length multiple as that of said engaged one wrapped and unwrapped wires of the multiples of said first and second portions, separating another of the wires from the engaged unwrapped another multiple of the inner lay of said first portion and wrapping said another wire in the space vacated by the unwrapped another wire of the another multiple of the inner lay of said second portion and lock the wrapped another wire to the unwrapped another wire of the inner lay thereof, removing a segment of the rubber

unwrapped another wire of the another multiple of the inner lay of said second portion and lock the wrapped another wire to the unwrapped another wire, repeating in sequence the above recited steps of separating and unwrapping and separating and wrapping of the remaining multiples of the inner lay of said second portion and of the remaining multiples of the inner lay of said first portion but with each of the resulting complementary locked wrapped and unwrapped multiples of said first and second portions spaced the same length from each other as that of said one and another complementary multiples, welding each of said one, another, and each of the remaining wrapped wires to the adjacent wires to form a unitary inner lay, wrapping the folded back multiples of the outer lay of said second portion over said unitary inner lay, subdividing the free end portions of the wrapped folded back multiples of the outer lay of said second portion into multiples the same as that of the folded back multiples of the outer lay of said portion and engaging each of the subdivided multiples with one of the folded back multiples of the outer lay of said first portion, unwrapping one of the subdivided multiples of the outer lay of said second portion until it is adjacent to and spaced a predetermined length from the terminating point of said second portion, wrapping the engaged one of the folded back multiples of the outer lay of said first portion in the space vacated by the unwrapped one multiple of said second portion with the free end portion engaging said unwrapped one multiple of the outer lay of said second portion, unwrapping another of the subdivided multiples of the outer lay of said first portion until it is adjacent to and spaced a length from said engaged one wrapped and unwrapped multiples of said outer lays of said first and second portions corresponding to that of the last mentioned said engaged one wrapped and unwrapped multiples, wrapping the engaged another of the folded back multiples of the outer lay of said first portion in the space vacated by the unwrapped another multiple of said second portion with the free end

portion engaging said unwrapped another multiple of the outer lay of said second portion, separating one of the wires from the engaged unwrapped one multiple of the outer lay of said second portion and unwrapping said one wire until it is adjacent to and spaced a multiple part of the length of the spacing of the engaged said one wrapped and unwrapped multiple of the outer lays of said first and second portions from the terminating point of said second portion, separating one of the wires from the engaged wrapped one multiple of the outer lay of said first portion and wrapping said one wire in the space vacated by the unwrapped one wire of the one multiple of the outer lay of said second portion with the free end portion engaging said unwrapped one wire of said last mentioned one multiple, separating another of the wires from the engaged unwrapped another multiple of the outer lay of said second portion and unwrapping said another wire until it is adjacent to and spaced a length multiple from said engaged one wrapped and unwrapped wire corresponding to the same length multiple of spacing of the last mentioned engaged wires from the terminating point of said second portion, separating another of the wires from the engaged wrapped one multiple of the outer lay of said first portion and wrapping said another wire in the space vacated by the unwrapped another wire of the one multiple of the outer lay of said second portion with the free end portion engaging said unwrapped another wire of said last mentioned one multiple, and lock the wrapped another wire to the unwrapped another wire, and welding each of said one and another wires to the adjacent wires and form a unitary outer lay.
